FIRING MECHANISM FOR AUTOMATIC RIFLES

Marc Jourdat, St.-Etienne, France, assignor to Societe a responsabilite limitee Gevarm, Saint-Etienne (Loire), France, a French corporation

Application April 11, 1952, Serial No. 281,746

Claims priority, application France April 17, 1951

3 Claims. (Cl. 89—140)

Automatic rifles as produced hitherto include an intricate mechanism, the parts of which are difficult to machine and are consequently expensive.

The automatic rifle forming the object of my invention has for its object to remove these drawbacks and comprises a bolt chamber to the front of which is screwed the gun barrel and wherein the actual rifle bolt is slidably fitted and urged forwardly by a spring while the bolt carries at its front a rod-shaped extension adapted to strike the cartridge in the barrel, said rod-shaped extension being slidably fitted inside an extension of reduced diameter of the bolt chamber while there is pivotally secured to a carrier member or receiver rigid with the bolt chamber a tumbler adapted to release the rifle bolt out of its rear inoperative position when said tumbler is released by the trigger.

Accompanying drawings illustrate by way of example a preferred embodiment of my invention. In said drawings:

Fig. 1 is a longitudinal cross-section of the rifle illustrated in its cocked position before firing.

Fig. 2 is a cross-section thereof through line II—II of Fig. 1.

Fig. 3 is a longitudinal cross-section of the rifle shown at the moment of the automatic positioning of the cartridge just before firing.

Fig. 4 is a partial cross-sectional view of the cocking means for the rifle bolt before the latter recoils or kicks.

Fig. 5 illustrates in longitudinal cross-sectional view the rifle at the moment of the recoil of the rifle bolt and of the automatic ejection of the empty cartridge case.

Fig. 6 is a cross-section through line VI—VI of Fig. 5.

Fig. 7 is an outer plan view corresponding to Fig. 5.

Fig. 8 shows the cocking device for the rifle bolt in the case of the firing of a burst.

Fig. 9 is a perspective view of the rocking spindle controlling selectively the firing of a burst or of separate shots.

The rifle illustrated includes a gun barrel 1 that is threaded at its rear so as to be screwed into the rifle bolt chamber 2. The latter which is of cylindrical shape is bored so as to form two successive elementary chambers 2¹ and 2² opening into one another through a shoulder separating them, the diameter of the front chamber being less than that of the rear chamber: the bolt 3 is adapted to slide in said bolt chamber and is arrested in its forward movement by the shoulder between the two elementary chambers. The bolt 3 includes a cylindrical body 3¹ that is slidably fitted inside the large diameter chamber 2 and a front extension assuming the shape of a cylindrical rod 3² acts as a piston inside the front chamber 2¹ the inner diameter of which corresponds to the diameter of the bead of the cartridge. The bolt 3 carries a cocking lever 4 (Fig. 7) that projects outwardly of the chamber 2, while it is longitudinally guided inside a slot 2³ of the latter.

The forward stroke of the bolt 3 is obtained by means of the coil spring 5 that is wound round the shouldered

2

rod 6 engaging an axial bore provided in the bolt and in its associated rod. The rod 6 abuts through its shouldered end against the plug 7 that is screwed into or else secured through notches to the rear cover of the chamber 2.

The lower portion 2⁴ of the elementary chamber 2¹ is recessed in order that the upper part of a cartridge clip or charger 8 designed in the conventional manner may enter it, said charger being secured through a rocking bracket 9 pivotally carried by a parallelopipedic carrier or receiver 10 extending underneath the bolt chamber.

The carrier 10 is rigidly secured to the chamber 2 by means of a screw 11 or any other suitable means. This carrier includes at its rear end a trigger guard 12 and it is recessed at 10¹ in order to house the automatic cocking device.

This automatic cocking device includes a trigger 13 that is submitted to the vertical thrust of a coil spring 13¹. This trigger 13 is housed inside the carrier 10 and it is pivotally secured over a transverse pivot pin 14 engaging a vertically elongated port 13² provided in said trigger. The front end of the trigger forms a nose 13³ lying, before the firing, over and in contact with the nose 15¹ of the sear 15. The latter assumes the shape of a rectangular plate and engages through its upper end the inside of the chamber 2; it is pivotally secured over a transverse pivot pin 16 of the carrier or receiver 10, said pivot pin engaging a vertically elongated port 15² in said trigger plate. The sear 15 is provided in its lower portion with a further elongated port 15³ through which passes an angularly shiftable spindle or pivot pin 17 through which it is possible to produce the firing either as a burst or as a series of separate shots. The sear 15 is also subjected to the action of a coil spring 18 engaging a stud 19 on the carrier 10 and adapted to urge the sear forwardly and to the action of a compressed coil 20 urging the sear upwardly into its cocked position.

In order to cock the rifle, the bolt is urged rearwardly either by hand through actuation of the cocking lever 4 or automatically as described hereinafter, until the shoulder 3³ on the bolt is engaged by the upper end of the sear 15. The latter that forms a stop, that is capable of receding, rocks with reference to the pivot pin 16 under the action of the torque generated by the spring 5 urging the bolt forwardly until the front surface of the elongated opening 15³ in the rocking sear abuts against the flat side of the oblong spindle 17 as illustrated by the arrow A of Fig. 1.

When firing (see Fig. 3) and upon depression of the trigger 13 in the direction of the arrow B of Fig. 3 the sear 15 rocks as shown by the arrow C and it revolves round the pivot pin 16 until the front shoulder 3³ of the bolt is released by said sear. However, the trigger 13 is provided on its upper surface with an adjustable screw 22 that abuts just before the release of the bolt 3 against the lower surface of the bolt chamber 2 whereby, after contact of said lower surface with the screw 22, a continued depression of the trigger 13 produces a further angular shifting thereof by reason of the clearance of the pivot pin 14 with reference to the port 13².

This further shifting of the trigger is felt by the hunter using the rifle, by reason of the different values of the successive stresses exerted on the trigger. The thrust thus executed in two stages warns the hunter of the incipient actual firing.

At the moment of firing, the released bolt is suddenly urged forwardly by the spring 5, whereby it comes into contact through the front end of the rod 3² with the case of the uppermost cartridge X projecting above the upper end of the cartridge charger 8.

During its forward stroke, the rifle bolt 3 urges forwardly said cartridge X that is guided inside the front chamber 2¹. At the end of the stroke, the cartridge

engages the chamber 1¹ of the gun barrel 1 until the bead of the cartridge is in contact with the rear end of the barrel 1. At this moment, the sudden stopping of the cartridge X provides the desired percussion by reason of the inertia developed by the high speed movement of the bolt. The rod 3² is provided at its end with a projecting nose 3⁴ that strikes the cartridge along its annular surface.

After the firing, the pressure of the explosion gases urges rearwardly the bolt 3 while the cartridge case is extracted and ejected automatically.

To this end and as shown in Fig. 5, the bolt 3 as it moves rearwardly uncovers the flaring lateral opening 2⁵ in the bolt chamber 2. The empty case urged rearwardly together with the bolt 3 escapes then suddenly through the said opening 2⁵, is blown outwardly and ejected.

When the firing is at an end (Fig. 4) the sear 15 is urged by the coil springs 18 and 20, into a pivoting motion with reference to the pivot pin 16 in the direction of the arrow D. During this pivotal movement, the nose 15¹ of the sear releases the nose 13³ of the trigger 13 whereby said trigger and sear no longer engage each other. The sear 15 is thus urged vertically by the springs 18 and 20 which allows a further automatic cocking of the rifle after the recoil of the bolt 3 to the rear of the sear. The trigger 13 which is now released by the automatic cocking device is returned to its firing position by the spring 13¹. The movement of the sear 15 which rocks with reference to the spindle 16 is limited in both directions by the opposite surfaces 17¹ of the oblong spindle 17 engaging the elongated port 15³. The spindle extends outwardly as a crank lever 17² which may be angularly shifted in order to obtain either a burst firing or a succession of separate rounds. In the first case, the spindle 17 should be turned by 90° as shown in Fig. 8 so that the flat lateral surfaces of said spindle fit exactly across the elongated port 15³ of the sear so as to prevent any rocking of the latter. In this position, the actuation of the trigger 13 only provides for the vertical shifting of the sear 15 as shown by the direction of the arrows E and consequently this produces a burst firing, as no preliminary action on the trigger is then required.

The automatic rifle according to my invention is of an extremely simple execution by reason of the simple nature of its different parts most of which may be obtained by turning from the bar or the like standard mechanical operations.

On the other hand, this rifle includes none of the standard members known and used hitherto such as the extractor, the ejector, the movable striker, the slope feeding the barrel and the like.

What I claim is:

1. In an automatic rifle, in combination: a bolt chamber; a bolt slideable in said chamber; a main spring in said chamber and urging said bolt forward; a receiver rigid with said chamber; a sear member in said receiver, normally engaging the bolt against the action of said spring; in said sear member, a first elongated slot substantially orthogonal to the bolt; a first pivot pin rigid with said receiver, said first slot engaging said pivot pin and being adapted to slide on said pivot pin in directions substantially orthogonal to the bolt; a trigger in said receiver, adapted to engage yieldingly said sear member and movable with respect to said sear member; in said trigger, a second elongated slot substantially orthogonal to the bolt; a second pivot pin rigid with said receiver and engaging said second slot, whereby said trigger is adapted to slide over said second pivot pin in directions substantially orthogonal to the bolt; said trigger being held directly by said sear member when the latter engages the bolt against the action of the main spring; said trigger being adapted, upon depression, to release said sear member from engagement with the bolt; at least one spring means be-

tween said receiver and said sear member and adapted to urge said sear member against the bolt upon recoil thereof, and to control the operative and inoperative positions of said sear member relative to the bolt, the bolt chamber and the trigger; said bolt, during its forward and recoil directions of motion, urging said sear member outside said bolt chamber until said bolt has returned to its rearward inoperative position, at which said one spring means urges said sear member in locking engagement with said bolt, and at which said trigger has been released from engagement with said sear member and returned to its inoperative position.

2. In an automatic rifle, the combination as claimed in claim 1, comprising further: elastic means between the bottom wall of said receiver and the lower face of said trigger, forward of said second pivot pin and adapted to urge said trigger upwards over said second pivot pin; an adjustable screw projecting from the upper face of said trigger rearwards of said second slot, and adapted to abut against the lower surface of said bolt chamber upon rocking of said trigger around said second pivot pin during the early stage of depression of said trigger prior to the release of the bolt; the duration of said early stage being controlled by the height of the projection of said screw out of said upper face; whereby, during a continued depression of said trigger beyond said early stage, said screw causes the forward end of said trigger to pivot around said second pivot pin against the action of said elastic means, thereby causing said trigger to actuate said sear member to release said bolt and indicating to the user the precise timing of bolt-release and striking in relation to the early stage and continued depressions respectively of said trigger.

3. In an automatic rifle, the combination as claimed in claim 1, comprising further: in said sear member, a third elongated slot disposed below, and substantially coaxial with, said first slot, and substantially orthogonal to said bolt; a rotary spindle supported by the walls of said receiver and passing through said third slot; said third slot having a transverse width substantially greater than that of said first slot; said spindle having two flat parallel side walls forming an intermediate portion located within the walls of said receiver and adapted to cooperate with said third slot; the width of said intermediate portion being substantially equal to the transverse width of said third slot; hand operated means connected to said spindle and adapted to shift said spindle into a first position for which the flat side walls of said intermediate portion are substantially orthogonal to said bolt, thereby allowing shifting and biasing of said sear member around said first pivot pin, and into a second alternative position for which said flat side walls of said intermediate portion extend transversely across said third slot and engage the side walls of said third slot to allow only a vertical shifting of said sear member, whereby said automatic rifle may be operated for burst firing when said spindle is in said second position and for controlled firing when said spindle is in said first position.
